UNITED STATES PATENT OFFICE.

ARTHUR B. DAVENPORT, JR., AND CHAUNCEY REIGART, OF PHILADELPHIA, PENNSYLVANIA, ASSIGNORS TO WILLIAM WHARTON, JR., & COMPANY, INCORPORATED, OF PHILADELPHIA, PENNSYLVANIA, A CORPORATION OF PENNSYLVANIA.

ACTUATING AND LOCKING MECHANISM FOR TONGUE-SWITCHES.

No. 922,396.

Specification of Letters Patent.

Patented May 18, 1909.

Application filed July 20, 1908. Serial No. 444,450.

To all whom it may concern:

Be it known that we, ARTHUR B. DAVENPORT, Jr., and CHAUNCEY REIGART, citizens of the United States, residing in Philadelphia, Pennsylvania, have invented certain Improvements in Actuating and Locking Mechanism for Tongue-Switches, of which the following is a specification.

The object of our invention is to construct a switch mechanism in such a manner that the tongue will return automatically to the position in which it is set after it has been forced open by the passing of car wheels through the switch. The tongue can be set to be returned either against the head of the rail or against the guard when opened the full width or can be set so as to return either to the rail side or to the guard side of the switch. This object we attain in the following manner, reference being had to the accompanying drawings, in which:—

Figure 1, is a plan view of a tongue switch; Fig. 2, is an enlarged sectional view on the line 2—2, Fig. 1; Fig. 3, is a plan view 25 of the mechanism illustrated in Fig. 2; Figs. 4, 5, 6 and 7 are diagram views illustrating different positions of the mechanism; and Figs. 8 and 9 are detached perspective views of detail parts of our device.

30 A is a switch structure.

A' is the tongue pivoted at α to the switch structure.

α' is the rail and α^2 is the guard.

B is the box situated at one side of the 35 switch structure A and mounted in this box is the mechanism for actuating the switch tongue. In switch structures of this type, it is desirable to hold the switch tongue against the guard as shown in Fig. 1, or 40 against the rail so that when the tongue is moved by a wheel passing through the switch it will return to the position to which it is set. On the other hand it is desirable in some instances to allow the tongue to 45 turn either to the guard or to the rail according to the position in which the tongue is thrown, so that if the tongue passes the center it will be thrown to the opposite side, but if it does not pass the central position 50 it will return to the same side in which it was placed originally.

In the construction which we will proceed to describe we provide mechanism for returning the tongue to a predetermined po-

sition depending upon the arrangement of 55 the mechanism in the switch box. Attached to the tongue A' is a rod C, screw threaded in the present instance, and having on it nuts c placed on one side of the tongue A' while a sleeve C' is mounted on the rod, and 60 bears against the opposite side of said tongue. A nut c' on the rod clamps this sleeve firmly in place and it is obvious that by adjusting the nuts c—c' the position of the tongue can be fixed as desired. The rod C is 65 pivoted at c^2 to a bell crank lever D Fig. 3, and this lever in turn is pivoted to bearings on the box; the pivot pin d extending through the upper bearings and through the lever. Said lever is made in two parts d' d' connected together by a web d², as shown in Fig. 8, and mounted in the lever is a loose cam E having an opening e through which passes the pivot pin d. This cam has at its outer end two curved portions e'—e² giving 70 it a heart shaped form and is provided with a series of holes e³, three in the present instance; there being a pin E' which passes through holes in the arms d' and through any one of said holes d³ of said cam E. By 75 adjusting this pin the switch tongue can be adjusted to return to either the rail side or guard side of the switch structure or to either side, if shifted past the center.

In line with the cam E is a roller f mounted 85 on a pin f' carried by a plunger F movably mounted in a bearing G and having a rounded end resting in a cavity b in the casing B. The plunger F is forked at the outer end to form the bearings for the pin f' 90 and the shank F' of the plunger is screw threaded for the reception of a nut f², between which nut and the bearing G is a coiled spring H. By adjusting the nut the pressure of the spring H can be increased or 95 decreased as desired.

The roller f is mounted between the two cheeks b' projecting from the casing, and has a very slight lateral motion so as not to bind between said cheeks, otherwise the roller 100 and its plunger are free to bear against either face e' or e² of the cam E. Thus it will be seen that if the tongue A' is set so as to bear normally against the guard as in Figs. 1 and 2, then the pin E' is passed 105 through one of the holes, as illustrated in Fig. 4, and the roller f bears against the cam face e² so that when the tongue is pushed by

the flange of a wheel away from the guard the cam E will ride over the face of the roller f to the position shown in Fig. 5. In this position the tongue is shifted entirely 5 over in contact with the rail side a^2 of the switch structure, but as the center point x of the cam E has not passed the center of the roller, the spring plunger will exert such pressure on said cam as to return the tongue 10 to its position against the guard a^2 as soon as it is released from the control of the wheel.

If it is desired to normally hold the tongue against the rail side of the switch structure then the pin E' is placed in the opposite end 15 hole e^3 as in Figs. 6 and 7; Fig. 6 showing the position of the parts when the tongue is resting against the side of the structure. When the tongue is moved away from the rail by a car wheel and moved against the 20 guard a^2 , then the parts are in the position shown in Fig. 7, but as the point x has not passed the center of the roller, the tongue will be returned to its normal position by the pressure of the spring. When the pin is 25 in the center hole as shown in Fig. 3, the switch tongue will, if moved past the center in either direction, be returned to one side or the other of the switch structure according to whether or not the point x has passed the 30 center of the roller.

We claim:

1. The combination in a switch actuating and locking mechanism for tongue switches, of a switch structure, a tongue, a rod connected to the tongue, a lever, an adjustable cam on the lever, and a plunger pressing against the cam to return the switch tongue to its normal position.

2. The combination of a switch structure, 40 a tongue pivoted thereon, a rod extending laterally from the tongue, a lever connected to the rod, an adjustable arm pivoted on the same center as the lever and having bearing faces, with a spring plunger adapted to press 45 against said bearing faces so as to return the tongue to its normal position after it has been moved therefrom.

3. The combination of a switch structure having a pivoted tongue, a rod extending 50 from the tongue, a box at one side of the structure, a bell crank lever pivoted to bearings in the box, said rod being connected to one arm of the bell-crank lever, an adjustable cam attached to the other arm of the 55 said bell crank lever and forming a continuation thereof, said cam having bearing faces, and a spring plunger adapted to press against one of said bearing faces so as to cause the tongue to return to its normal position after it has been moved therefrom.

4. The combination of a switch structure having a pivoted tongue, a box at one side of the structure, a bell crank lever mounted in the box, a rod connecting the bell-crank lever 65 with the switch tongue, a cam pivoted to the

same pivot as the lever and adjustably attached to the other arm of said lever, said cam having a bearing edge more extended at the center than at the sides, a spring plunger adapted to rest against the said bearing edge 70 so that when the tongue is moved the pressure of the plunger will cause the lever to return the tongue to its normal position.

5. The combination of a switch structure 75 having a pivoted tongue, a box at one side of the switch structure, a bell crank lever pivoted to bearings in the box, a rod connecting one arm of said bell crank lever with the switch tongue, a cam mounted on the same pivot as the bell-crank lever and having three perforations, a pin adapted to an opening in the other arm of the bell crank lever and to any one of the perforations in the 80 cam, said cam having end bearing surfaces so as to cause the tongue to normally rest 85 upon one side of the switch structure.

6. The combination in a switch structure 90 having a pivoted tongue, a bell-crank lever mounted in suitable bearings, a rod connecting the tongue with one arm of the bell-crank lever, a cam pivoted to the same pivot as the bell-crank lever and having a series of openings, a pin adapted to an opening in the other arm of the bell-crank lever and to any one of the openings in the cam, the end 95 of the cam being substantially heart-shaped, and a spring plunger adapted to rest against the bearing edge of the cam.

7. The combination of a switch structure 100 having a movable tongue, a bell-crank lever pivoted at one side of the switch structure, a rod connecting one arm of the bell-crank lever with the tongue, an adjustable cam attached to the other arm of the bell-crank lever, and being provided with a bearing 105 edge, a plunger, a spring adapted to force the plunger toward the pivot of the bell-crank lever, and a roller carried by the plunger adapted to bear against the edge of the cam.

8. The combination of a switch structure 110 having a movable tongue, a box at one side of the switch structure, a bell-crank lever adapted to bearings in the box, a rod connecting the bell-crank lever with the tongue, 115 said lever being made in two connected parts, a cam mounted on the same pivot as the bell-crank lever and situated between the two parts of said lever, a series of openings in the cam adapted to align with openings in 120 one arm of the bell-crank lever, a pin connecting the cam to the lever, the end of the cam being shaped to form a central projection and curved bearing edges, and a plunger having a roller adapted to bear against 125 the edges of the cam.

9. The combination in a switch structure 130 having a movable tongue, a box at one side of the switch structure, a bell crank lever mounted in bearings in the box, a rod con-

necting one arm of the bell-crank lever with the tongue, a cam mounted on the same pivot as the bell-crank lever and adjustably connected to the other arm of said lever, the 5 outer edge of said cam being substantially heart shaped, a plunger mounted to be movable toward and from the center of the bell-crank lever, a spring back of the plunger, means for adjusting the spring, a flanged 10 roller carried by the head of the plunger and adapted to rest against the bearing edge of the cam, the parts being so proportioned that the plunger will allow the switch tongue to yield, but will throw it back in contact 15 with one side or the other of the switch structure.

10. The combination of a switch structure, a pivoted tongue, a box at one side of the switch structure, a vertical pivot in said box, 20 a bell-crank lever mounted on the pivot, a rod connecting one arm of the bell-crank lever with the switch tongue, the said lever being made in two connected parts, a cam mounted between said two parts and adapted

to the same pivot as the bell-crank lever, 25 said cam having three holes therein, a hole in one arm of the bell-crank lever, a pin adapted to the hole in said lever and to one of the holes in the adjustable cam, a spring plunger mounted in the box and having a 30 curved roller adapted to rest against the bearing edge of the cam, a bearing in the rear end of the spring, adapted to a socket at the rear end of the box, with two cheeks on the box to guide the plunger, the parts being 35 so arranged that the plunger will tend to hold the switch tongue against one side or the other of the switch structure and allow it to yield under pressure.

In testimony whereof, we have signed our 40 names to this specification, in the presence of two subscribing witnesses.
